PORTABLE PICTURE TRANSMISSION APPARATUS

Harold Carlson, Rutherford, N. J., assignor to
The Associated Press, New York, N. Y., a corporation of New York

Application June 4, 1936, Serial No. 83,441

22 Claims. (Cl. 178—13)

This invention relates to a portable picture transmission apparatus.

An object of this invention is to provide a compact picture scanning mechanism of light weight which can be used in conjunction with present non-portable apparatus in newspaper offices.

A further object is to provide a novel method of rotating the picture drum and moving it axially in synchronism with other machines, portable, or non-portable which may be in circuit therewith.

Still another object is the provision of a simple, rugged, and inexpensive mechanism which may be constructed from standard parts with a minimum of special machine work.

In a well-known picture transmission system in use by a number of newspapers, the characteristics of the picture are transmitted over telephone circuits as modulations of a carrier wave at voice frequency. The present invention contemplates the use of a vacuum tube driven fork oscillator of known design operating at a suitable frequency, such as 2400 cycles to drive a synchronous motor for turning the picture drum and vibrating a light valve, also of known construction.

The present invention provides a picture scanning mechanism which can be constructed from standard parts to scan a picture as closely or as coarsely as desired.

In the embodiment shown, only one axial feed rate is contemplated, that is, 200 turns per inch, but it will be readily seen that with a few minor changes that the machine may be adapted to scan more closely or less closely than this rate.

The invention will now be described with the aid of the accompanying drawings of which there are four sheets.

Figure 1 is a front elevation of a picture transmitter constructed according to the present invention.

Figure 2 is a top view.

Figure 3 shows details of the clutch mechanism.

Figure 4 is a vertical section taken through 4—4 of Figure 2.

Figure 5 is an end view of the drum showing details of a lead nut.

Figure 6 is a top view of the clutch mechanism.

Figure 7 is a vertical section taken through 7—7 of Figure 1.

Figure 8 shows the clutch engaging lever.

Figure 9 is a schematic diagram of a circuit arrangement suitable for use with the present invention.

Referring now to the drawings:

Secured to base 1 are upright members 2, 3, and 4, which serve to support the various parts of the machine.

The main shaft, a single unit, consisting of a round section 5 and a square section 6 extends through upright member 3 and is supported by suitable bearings in members 2 and 4.

A friction device 7 is secured to one end of the main shaft for the purpose of preventing back lash in the various parts of the mechanism. The friction device shown is a modification of the well-known friction clutch used on start stop printing telegraph distributors.

The arrangement shown consists of two driven sections 8 and 9 and a stationary section having an arm 10 which tends to turn with the shaft but is prevented from doing so by pin 11 in upright 4. The stationary and moving sections are separated by suitable friction washers 12 and 13. The particular assembly can be taken down by removing thumb screw 14.

The main shaft is driven by synchronous motor 21, (Figure 2) which is secured to the members 3 and 4 in such a manner that it can be readily detached for greater portability.

The motor is provided with three legs which are secured respectively in U-shaped openings in brackets 22 by screws 23, two of which are shown. The brackets are in turn attached to upright members 3 and 4 by screws 24 shown in section in Figure 1.

The motor 21 is driven in the present embodiment by 2400 cycle alternating current. In order to start the motor it is necessary that it be brought up to speed or slightly beyond its normal synchronous speed by some external means. The present invention provides for starting the motor as follows:

To the shaft 25 of motor 21 is secured a small wheel 26 having a periphery of rubber, leather, or other suitable material.

A lever 27 pivoted on screw 28 and supported by a stud 29 attached to the motor shell carries at one end a wheel 30 which is free to turn on bearing screw 31. Wheel 30 is of considerably greater diameter than wheel 26 which it overlies, but normally does not engage, due to spring 32 supported between post 33 in the motor shell and post 34 in the lever which holds the wheels out of engagement with each other. The periphery of wheel 30 may, if desired, be of a friction material.

When starting motor 21, wheels 26 and 30 are brought into engagement by rotating lever 27

on its pivot and wheel 30 may then be turned by means of handle 35, driving wheel 26 on the motor shaft at a considerably greater speed.

A yielding connection is provided between the 5 motor shaft and the mechanism driven thereby in order to reduce the effect of any slight irregularities that might occur in the operation of the motor.

The motor shaft 25 projects beyond disc 36 10 which is secured thereto. Disc 37 is secured to shaft 38 which also carries worm 39 fast thereon. Motor shaft 25 extends into sleeve 40 which is integral with 37 and 38 sufficiently to support this assembly, but is not otherwise secured there- 15 to except by springs 41 which form a yielding connection between the motor and the worm.

Worm 39 drives worm wheel 42 fast on the round section 5 of the main shaft. Secured to the main shaft adjacent to wheel 42 is a gear 20 50 which meshes with gear 51 on stub shaft 52, supported by upright member 3.

Gear 51 is free to turn on shaft 52 and is fast to disc 53 which is part of the driving side of a clutch mechanism which may, at will, form a 25 fixed connection between gear 51 and gear 54 also supported by shaft 52.

Gear 54 is meshed with gear 55 fast to sleeve 30 56, in which shaft 5 is free to turn. The sleeve is further supported externally by bearing 57 in upright member 3.

Secured to sleeve 56 is a threaded sleeve or hollow lead screw 58 which turns with sleeve 56 on the round section 5 of the main shaft between upright 3 and a shoulder formed at the 35 junction of the square section 6 and the round section 5 of the main shaft.

Drum 59 which is rotated and moved axially on the main shaft is provided with a plate 60 at one end, which carries a lead nut split in two 40 sections, 61 and 62, Figure 5. The part 62 is attached to plate 60 by shoulder screws 63 which extend through slightly elongated holes in 62.

One end of compression spring 64 extends into 45 an opening in 63 and the opposite end into a similar opening in a block 65 secured to plate 60, causing the lead nut to engage the hollow screw 58 at all times, thus eliminating back lash and lost motion between these parts.

The opposite end of the drum is supported by 50 plate 66 having an opening which fits closely the square section 6 of the main shaft, yet permits the drum to move axially thereon with a minimum of friction.

The clutch between gears 51 and 54 referred to 55 above consists of a driving section supported by plate 53 secured to gear 51, and a driven section consisting of a toothed wheel 81 secured to gear 54.

Mounted on plate 53 is a pawl 67 which pivots 60 on screw 68. The pawl is provided with two notches, 69 and 70, which cooperate with spring pressed detent 71 pivoted on screw 72 in plate 53.

The detent serves to hold the pawl in either of 65 two positions depending on whether the clutch sections are connected or disconnected.

Pawl 67 has an arm 73 which extends almost to the edge of disc 53. A lever having offset arms 74 and 75, Figure 8, is pivoted to plate 53 70 by screw 76. Arm 75 may move between stop pins 77 and 78, but is normally held against pin 77 by spring 79.

Pawl 67 is provided with teeth 80 which when 75 detent 71 rests in notch 69 mesh with similar

teeth in wheel 81 (Figure 4) which is rigidly secured to gear 54.

When the detent rests in notch 70, gears 51 and 54 are disconnected.

The following arrangement is provided for operating the clutch while the machine is in motion.

A bifurcated lever 86 having a handle 87 is pivoted on stud 88 to the frame of the machine. The lever is positioned by a centering device consisting of a second lever 89 also pivoted on stud 88. Springs 90 secured to pins 91 which overlie the arms of lever 86 serve to hold the assembly in a center position.

Lever 86 may be rotated on its pivot in either 15 direction, the limit being determined by stop pins 92 and 93.

When handle 87 is raised, the end of arm 94 of lever 86 is in the plane of rotation of the offset arm 75 of the clutch operating lever and during the course of clockwise rotation of disc 53, as shown in Figure 3, 75 will engage 94 causing the rotation of 75 on its pivot as indicated by the dotted lines in the drawings, and under these conditions if the clutch has been previously disengaged, the arm 74 of the lever will engage arm 73 of the pawl overthrowing the detent and causing the teeth 80 of the pawl to mesh with the teeth on wheel 81, thus throwing in the clutch.

If handle 87 were similarly rotated, and the 30 clutch were already in, nothing would happen except that arm 75 would be tripped at each revolution of the mechanism.

The clutch is thrown out or disconnected as follows: When handle 87 is depressed so that 35 lever 86 rests against stop 92, then the offset arm 95, Figure 6, is in the path of rotation of arm 73, so when the clutch is in, during the course of rotation, with handle 87 depressed, arm 95 will engage arm 73 of pawl 67 rotating pawl 67, and overthrowing it sufficiently for detent 71 to drop into notch 70, positioning the pawl so that arm 73 will clear 95 if 67 is kept depressed during subsequent turns of the machine.

Referring now to Figures 1 and 7: A lever 96 45 is supported by pivot 97 secured to the frame of the machine. Spring 98 tends to hold arm 100 shaped like a brake shoe out of contact with the hub of gear 55 which it overlies. A stud 99 is provided as a stop for 96.

The shoe 100 may be manually pressed against 50 the hub of gear 55 to stop the wheel when the clutch is out in order to restore the drum to an initial or starting position. This operation will be described in detail below.

Operation

Let it be assumed that it is desired to cause the drum to move axially 1/200 of an inch per revolution.

By referring to the drawings it will be seen that a positive direct drive is provided for rotating the drum through worm 39 and worm wheel 42, the latter being secured to the main shaft which has a square section 6 extending through 65 a square opening in the drum end plate 66.

It will be understood, also, that with the clutch out, or disconnected, that the drum will revolve in whatever position it happens to be, without feeding axially.

For the purpose of illustration we will assume that sleeve or hollow lead screw 58 is provided with 20 threads per inch, this being a standard thread of large size and easily cut.

With the present arrangement, if the drum 75

were turned and the sleeve prevented from turning, then the drum would move axially 1/20 of an inch with each revolution of the drum. Likewise, if the threaded sleeve 58 were rotating at a speed different from that of the main shaft, the drum would move axially in either direction, the direction and rate of axial movement being proportional to the difference in speed and direction of the relative movement of the main shaft 10 and the threaded sleeve.

In the present embodiment gears 50 and 51 have a like number of teeth, gears with 34 teeth having been selected.

Gear 54, however has 33 teeth, and gear 55 has 15 30 teeth.

With each revolution of the main shaft, and with the clutch in, gears 50, 51 and 54 make one revolution.

If gears 54 and 55 had a like number of teeth, gear 55 and sleeve 58 would also turn with the main shaft and the drum would revolve but not move axially. But this is not the case, since gear 54 is provided with 33 teeth and gear 55 has 30 teeth, so when 54 makes a complete revolution, gear 55 is turned 3 teeth or 36 degrees further, which is 1/10 of a turn, so therefore the drum will move axially 1/10 of 1/20 of an inch or 1/200 of an inch.

Obviously, with the arrangement just described, if the difference in speed between the lead screw and the main shaft were 1/20 of a revolution, an axial feed of 1/400 of an inch would be made at each revolution of the drum. Similarly, if the difference were 1/5 of a revolution, the axial feed 35 would be 1/100 of an inch.

After a picture has been scanned, it is necessary to return the drum to a starting point. This is readily accomplished with the present mechanism without stopping the device by rotating 40 lever 96 on its pivot so that shoe 100 rides against the hub of gear 55 holding the gear against rotation. This operation is performed with the clutch out. Under these conditions the drum is quickly returned to its initial position by the relatively 45 coarse thread on the lead screw at the rate of 1/20 of an inch for each revolution of the drum.

The device described above may be used with a known electro-optical system shown in Figure 9, in which the light from a source of illumination 50 101 is focused by lens 102 on the shutter of light valve 103 which vibrates under the influence of an alternating current from the vacuum tube driven fork oscillator 104, the alternating current being amplified by amplifier 105.

55 The pulsating light beam is focused by optical system 106 on mirror 107 which reflects a point of intense light on a picture secured to drum 59.

Light varying in intensity with the shade of the elemental areas of the picture is reflected 60 from the drum and focused by mirrors 108 and 109 on a photo electric cell 110, causing a pulsating current of varying amplitude to pass through amplifier 111, band pass filter 112, and attenuator 113, or any suitable network to line 65 114.

Vacuum tube driven fork oscillator 104 also produces an alternating current for driving motor 21. This current is amplified by amplifier 115 and passes therefrom by circuit 116 to the 70 motor.

Cam 117 on the main shaft cooperates with contacts 118 to momentarily short circuit the line and start all machines in synchronism, according to well known practice.

75 While but one illustrative embodiment of this

invention has been herein shown and described, it will be understood that numerous details of the arrangement may be altered without departing from the spirit of this invention as defined by the following claims.

What is claimed is:

1. In a device of the character described, a picture drum, means for supporting said drum, threaded nut means secured to said drum, differential driving means effective solely through the 10 instrumentality of said supporting means for causing the rotation of said drum and for imparting an axial feed thereto of a pitch differing from that of the threaded nut.

2. In a device of the character described, a 15 picture drum, a rotary shaft for supporting said drum, a threaded nut secured to said drum through which said shaft extends, and differential driving means effective solely through the instrumentality of said shaft for imparting an 20 axial feed to said drum at a rate differing from the pitch of said threaded nut.

3. In a device of the character described, a picture drum, a rotary shaft for supporting said drum having a rounded section and a non- 25 rounded section, threaded means concentrically disposed on said rounded section of said shaft, a threaded nut secured to said drum arranged to turn on said threaded section, and means effective solely through the instrumentality of said shaft 30 for imparting a rotary movement and also an axial movement of a different pitch from that of the threaded section.

4. In a device of the character described, a picture drum, a shaft forming an axis for said 35 drum, means for rotating said drum, means for moving the drum axially and means for stopping or reversing the axial movement of the drum without interrupting its rotary movement.

5. In a device of the character described, a 40 picture drum, a shaft forming an axis for said drum, and means effective solely through said shaft for rotating the drum and moving the drum axially, and means for stopping or reversing the axial movement of the drum without interrupting its rotary motion.

6. In a device of the character described, a picture drum, a shaft forming an axis for said 50 drum and means effective solely through said shaft for rotating the drum and for moving the drum axially at a rate suitable for scanning, and also for moving the drum axially at a rate greater than that for scanning.

7. In a device of the character described, a picture drum, a shaft forming an axis for said 55 drum, means effective solely through said shaft for rotating the drum and moving the drum axially at a rate suitable for scanning and for moving the drum axially at a rate greater than that for scanning without interrupting the rotary motion of the drum.

8. In a device of the character described, a picture drum, a support therefor comprising a shaft having a round section and a non-circular section, a threaded sleeve over said round section, a pair of end plates for said drum, one plate being provided with an aperture fitting the non-circular section of said shaft and the other being provided with threads to fit said threaded sleeve.

9. In a device of the character described, a picture drum, a support therefor comprising a shaft having a round section and a non-circular section, a threaded sleeve over said round section, a pair of end plates for said drum, one plate being provided with an aperture fitting the non- 75

- circular section of said shaft and the other being provided with threads to fit said threaded sleeve, and means to cause said drum to rotate and feed axially at a pitch differing from that of the threaded sleeve.
10. In a device of the character described, a picture drum, a support therefor comprising a shaft having a round section and a non-circular section, a threaded sleeve over said round section, a pair of end plates for said drum, one plate being provided with an aperture fitting the non-circular section of said shaft and the other being provided with threads to fit said threaded sleeve, and means for driving said shaft and said threaded sleeve at different rates from a common source of power.
11. In a device of the character described, a picture drum, a support therefor comprising a shaft having a round section and a non-circular section, a threaded sleeve over said round section, a pair of end plates for said drum, one plate being provided with an aperture fitting the non-circular section of said shaft and the other being provided with threads to fit said threaded sleeve, independent means for driving said shaft and said sleeve from a common source of power, and a clutch between one of said means and said source of power.
12. In a device of the character described, a picture drum, a support therefor comprising a shaft having a round section and a non-circular section, a threaded sleeve over said round section, a pair of end plates for said drum, one plate being provided with an aperture fitting the non-circular section of said shaft and the other being provided with threads to fit said threaded sleeve, independent means for driving said shaft and said sleeve from a common source of power, and a clutch between said sleeve and said source of power.
13. In a device of the character described, a picture drum, a support therefor comprising a shaft having a round section and a non-circular section, a threaded sleeve over said round section and driving means for producing a differential movement between said sleeve and said shaft and thereby producing an axial movement of said drum.
14. In a device of the character described, a picture drum, a support therefor comprising a shaft having a round section and a non-circular section, a threaded sleeve over said round section and driving means for producing a differential movement between said sleeve and said shaft in order to produce an axial movement of said drum at a rate suitable for scanning, and means for restraining the rotation of said threaded sleeve to cause the drum to move axially at a rate greater than that for scanning.
15. In a device of the character described, a picture drum, a support therefor comprising a shaft having a round section and a non-circular section, a threaded sleeve over said round section, means for rotating said sleeve and said shaft from a common source of power at different rates; clutch means and brake means cooperating with the sleeve drive mechanism whereby the drum may be moved axially on said shaft in opposite directions at different rates.
16. In a device of the character described, a picture drum, a support therefor comprising a shaft having a round section and a non-circular section, a threaded sleeve over said round section, a pair of end plates for said drum, one plate being provided with an aperture fitting the non-
- circular section of said shaft and the other being provided with threads to fit said threaded sleeve, a motor for driving said shaft, a gear on said shaft meshing with a first gear of a pair of idler gears, a gear secured to said sleeve meshing with the second gear of said pair, and means to operatively connect or disconnect the gears of said pair.
17. In a device of the character described, a picture drum, a support therefor comprising a shaft having a round section and a non-circular section, a threaded sleeve over said round section, a pair of end plates for said drum, one plate being provided with an aperture fitting the non-circular section of said shaft and the other being provided with threads to fit said threaded sleeve, a motor for driving said shaft, a gear on said shaft meshing with a first gear of a pair of idler gears, a gear secured to said sleeve meshing with the second gear of said pair, and means settable to become effective at a predetermined point in a cycle of operation to connect operatively one idler gear with the other.
18. In a device of the character described, a picture drum, a support therefor comprising a shaft having a round section and a non-circular section, a threaded sleeve over said round section, a pair of end plates for said drum, one plate being provided with an aperture fitting the non-circular section of said shaft and the other being provided with threads to fit said threaded sleeve, a motor for driving said shaft, a gear on said shaft meshing with a first gear of a pair of idler gears, a gear secured to said sleeve meshing with the second gear of said pair, and means settable to become effective at a predetermined point in a cycle of operation to disconnect one idler gear from the other.
19. In a device of the character described, a picture drum, a support therefor comprising a shaft having a round section and a non-circular section, a threaded sleeve over said round section, a pair of end plates for said drum, one plate being provided with an aperture fitting the non-circular section of said shaft and the other being provided with threads to fit said threaded sleeve, a motor for driving said shaft, a gear on said shaft meshing with a first gear of a pair of idler gears, a gear secured to said sleeve meshing with the second gear of said pair, a ratchet wheel disposed between said idler gears and secured to one of said pair, a pawl and supporting means therefor secured to the other gear of said pair, and a detent carried by said pawl supporting means for retaining said pawl in an engaged or disengaged position with said ratchet.
20. In a device of the character described, a picture drum, a support therefor comprising a shaft having a round section and a non-circular section, a threaded sleeve over said round section, a pair of end plates for said drum, one plate being provided with an aperture fitting the non-circular section of said shaft and the other being provided with threads to fit said threaded sleeve, a motor for driving said shaft, a gear on said shaft meshing with a first gear of a pair of idler gears, a gear secured to said sleeve meshing with the second gear of said pair, a ratchet wheel disposed between said idler gears and secured to one of said pair, a pawl and supporting means therefor secured to the other gear of said pair, a detent carried by said pawl supporting means for retaining said pawl in an engaged or disengaged position with said ratchet, and a lever for operating said pawl.

21. In a device of the character described, a picture drum, a support therefor comprising a shaft having a round section and a non-circular section, a threaded sleeve over said round section, means for rotating said sleeve and said shaft from a common source of power at different rates; clutch means and brake means cooperating with the sleeve drive mechanism whereby the drum may be moved axially on said shaft in opposite directions at different rates, and means for correcting back lash in the respective parts comprising a friction clutch.

22. In a device of the character described, a picture drum, a support therefor comprising a

shaft having a round section and a non-circular section, a threaded sleeve over said round section, means for rotating said sleeve and said shaft from a common source of power at different rates; clutch means and brake means cooperating with the sleeve drive mechanism whereby the drum may be moved axially on said shaft in opposite directions at different rates, and means for correcting back lash in the respective parts comprising a friction clutch having a rotary element secured to said shaft, and a nonrotary element retained by a supporting member for said shaft.
